PUSH BUTTON ELECTRIC SNAP SWITCH

Harry A. Douglas, Bronson, Mich., assignor to
 Kingston Products Corporation, a corporation
 of Indiana

Application May 31, 1934, Serial No. 728,283

13 Claims. (Cl. 200—67)

This invention relates to improvements in electric switches and more particularly to a snap action switch of the push button operated type to quickly break and make a circuit.

5 It is an object of this invention to provide a switch of this type which is compact, simple in construction and readily assembled.

With these and other objects in view, reference is made to the accompanying sheet of drawing which illustrates a preferred embodiment of this invention with the understanding that minor detail changes may be made without departing from the scope thereof.

In the drawing—

15 Figure 1 is a view in central vertical section of an embodiment of this invention, with parts illustrated in elevation.

Figure 2 is a similar view in section taken at right angles to Figure 1.

20 Figure 3 is a view similar to Figure 1, with parts broken away, illustrating the position of the circuit making and breaking mechanism just before the circuit is broken, and indicating how a third terminal can be embodied thereon.

25 Figure 4 is a detail view in section taken on the line 4—4, Figure 1.

Figure 5 is a detail view in section taken on the line 5—5, Figure 3.

30 Figure 6 is a view in reduced scale in section taken on the line 6—6, Figure 1.

As illustrated in Figures 1, 2, and 3, the switching mechanism is enclosed in a cup-shaped metallic cylindrical casing 1 having the end closure 2 provided with a central circular opening 3 for the reception of a shouldered push button 4 of insulating material having a flange 5 upon the bottom thereof to engage the inner side of the closure 2 to prevent the button 4 from passing therethrough, as shown. The under side of the button is provided with an axial recess 6 for a purpose hereinafter described.

The open end of the casing 1 is closed by a contact carrying disc 7 of insulating material which is held securely in position by a plurality of spaced apart fingers 8, preferably three in number, forming integral extensions of the casing wall which are passed through corresponding notches 9 in the periphery of the disc 7 and then bent over the outer surface of the disc to hold the same firmly against the end of the casing wall. The contact carrying disc 7 mounts two electric terminals 10 and 11, preferably of the snap terminal type disclosed in this applicant's prior copending application, Serial No. 713,713, filed March 2, 1934, adapted to be electrically

connected to electric conductors, not shown, upon the outer side of the disc 7. As shown, each terminal includes a rectangular block having a cylindrical extension which extensions are preferably reduced in diameter. When this type terminal is employed, it is desirable to provide the carrier disc 7 with circular apertures through which the reduced extremities of the terminals are passed and the metal of the end is then expanded or riveted upon the interior of the disc 7 to hold the terminals in place. The terminals 10 and 11 are mounted perpendicularly to the disc at equal distances from the center.

The center of the contact carrying disc 7 is provided with an integral rectangular projection 12 of insulating material upon its inner surface having sides perpendicular to the upper surface of the disc with the side adjacent the terminal 10 joined to an upwardly extending angular surface 13 terminating in a flat central transverse portion 14. An electric contact 15 in the form of a metallic strip is connected to the terminal 10, preferably by passing the reduced cylindrical portion thereof through an aperture provided therefor in the end of said strip, upon the outer side of the contact carrying disc. The other end of the strip is then passed through the disc 7 to embrace the adjacent side and angular surface 13 of the central projection 12 upon the inner side of the disc 7 with the upper surface of the strip terminating flush with the flat top of the central transverse portion 14. The upper surface of the insulating projection leading from the flat top of the transverse portion 14 opposite the contact strip 15 is continued downwardly therefrom at an angle similar to that formed by the upper surface of said strip for a similar distance and then curved upwardly to form a stop 16, for a purpose hereinafter described. The expanded or riveted head of the terminal 10 is preferably received in a recess provided therefor upon the inner surface of the disc 7 to be wholly received below that surface, for a purpose hereinafter described.

The switching mechanism is carried upon a U-shaped metallic bracket having a rectangular base 17 with a central cut out portion 18, cut out to receive the projection 12 of the disc 7, providing end portions 19, one of which extends over the countersunk expanded end of the terminal 10 and having the sides of the base 17 provided with integral outstanding perforated ears 20 and 21. The reduced cylindrical portion of the terminal 11 is passed through the apertured ear 20 with the end expanded or riveted upon the upper surface thereof while the other ear 21 is secured

to the disc 7 by a rivet 22 passing through the ear and disc with the metal of the ends expanded or riveted thereon. The inner side of the end portion 19 of the base extending over the terminal 10 is spaced apart from the contact 15 and the opposite end portion 19 is in engagement with the wall 12 of the central projection I of the disc 7. One of the end portions 19 is provided upon its inner side with an integral upwardly extending stop 23 bent back at an angle and spaced apart from the contact 15 to form a stop complementary to the stop 16 of the insulated projection I.

The ear bearing sides of the base are extended upward to form two similar arms 24 perpendicular to the base 17 and equally spaced from the axis of the casing 1 with each side of each arm provided midway its height with inwardly extending integral fingers 25. The switching device for alternately continuing the circuit from the terminal 11 to the contact 15 of the terminal 10 is mounted to oscillate upon a pivot 26 passing through apertures in the upper ends of the arms 24. The circuit making and breaking mechanism includes an oscillating actuator A caused to oscillate by an oscillating operator O.

The actuator A is mounted upon the pivot pin 26 passed through apertures in the arms 24 of the supporting bracket and includes two similar metallic actuating plates 27 adapted to receive the pivot pin 26 and depend therefrom in sliding engagement with the respective arms 24 of the supporting bracket and terminating short of the high point of the carrier disc projection I with a portion of the opposite longitudinal sides struck up at right angles to the main body to form right angular flanges 28 extending upward from the bottom leaving oppositely disposed similar outstanding arms 29 extending from the body of the plate, the longitudinal edges of the flanges 28 being adapted to engage the similar edges of the corresponding flanges on the respective plates 27. The actuator plates 27 are mounted upon the pivot pin 26 in similar longitudinally elongated bearings 30 allowing a sliding longitudinal movement of the plates about the pin 26. The upper surfaces of the actuator arms 29 lie in the same plane which passes slightly below the axis of the pivot pin 26 when the upper end of the bearing 30 is in contact with the upper surface of the pin 26. A spring housing 31 in the form of an inverted U is mounted between the plates 27 and embraced by the flanges 28. The extremities of the sides of the housing are provided with transverse flanges 32 adapted to pass under the lower extremities of the actuator flanges 28 with the terminations thereof inclined upwardly to engage the outer sides of the oppositely disposed actuator flanges on each side of the housing and position the base or top of the housing at a distance below the lower end of the actuator bearing 30. The housing 31 receives in sliding engagement therewith a detent 33 in the form of a rectangular casing closed at the lower end in a rounded nose 34 and open at the other end to receive a coil spring 35 bearing against the interior of the nose and top of the housing.

The actuator A is caused to oscillate by the movement of an oscillating operator O. The oscillating operator O is preferably formed of a flat strip of metal centrally struck up to form oppositely disposed similar angular flat surfaces 36 departing downwardly from its transverse center line terminating in upwardly extending tangential stops 37 with the opposite sides struck 75 downwardly to form depending perforated ears

38 adapted to be received between the actuator plates 27 and receive the pivot pin 26 and mount the operator for oscillation thereabout below the meeting edge of the surfaces 36 parallel with and in the same plane as the axis of the pivot and with the upper surfaces of the actuator arms 29 in contact with the under surfaces of the tangential stops 37 when the lower ends of the bearings 30 of the actuator are in engagement with the under side of the pivot pin 26. When the bridge 10 nose 34, actuator and operator have been assembled upon the supporting bracket, the fingers 25 of the bracket arms 24 are bent toward each other, as shown in Figure 2, to prevent the nose 34 from riding over the stop 23 of the base 17 15 or the stop 16 of the projection I.

Back and forth movement is imparted to the oscillating operator by the manual depression of a reciprocating operator 39 preferably of insulating material and in the form of a finger depending centrally from a body 40 extending transversely thereof with its top and bottom surfaces perpendicular to the center line of the finger 39 and with the top surface of the body 40 in engagement with the top 41 of a frame received 25 within recess 6 of the button 4. As shown in Figure 2, the frame includes sides 42 depending from each side of the top 41 to embrace the longitudinal sides of the body 40, and are jutted to form shoulders 43, and then continued downwardly and away from each other to join similar parallel portions 44 arranged equidistantly and parallel to the axis of the casing, with the lower portion of each provided with a central longitudinal slot 45 adapted to receive an extension 46 35 of the pivot pin 26 of the actuator and oscillating operator. The operating finger 39 is normally maintained with its center line coincident with the axis of the casing 1 by a coil spring 47 within the arms 44 of the frame having the lower coil 40 horizontal and anchored in recesses 48 provided adjacent each corner in the top of the bracket arms 24 with the convolutions of the spring decreasing in diameter until the top horizontal coil engages the lower side of the body 40 and shoulders 43 of the frame. The spring 47 normally maintains the body 40 in engagement with the flat top 41 of the frame and the top 41 in engagement with the bottom of the recess 6 in the button 4 and the flange 5 thereof in engagement 50 with the under surface of the casing closure 2. The lower end of the finger 39 is preferably pointed and in the position just described terminates short of the highest point of the angular surfaces 36 of the oscillating operator and is preferably guided above the transverse center thereof by extending the tops of the bracket arms 24 into inturned guiding flanges 49.

As shown in Figure 1, the top 41 of the frame is reduced in width and provided with curved 60 edges 50 tangential to the under side thereof and the vertical sides of the body 40 are formed on the arc of a circle concentric with the center of said body. The angular surfaces 36 of the oscillating operator O are so formed that, with 65 the parts in the position shown in Figure 1, a line from the point of departure of the curve 50 from the bottom of the top 41 of the frame through the lowermost point of the finger 39 will form an obtuse angle with the surface 36 on the same side of the casing axis, whereby upon depression of the button 4 causes the finger 39 to engage said surface and slide thereover to engage the stop 37 of the oscillating actuator and at the same time the top of the body 40 will move 70 75

about the curved end 50 of the top of the frame as a fulcrum. Upon continued depression of the button 4, the pivoted operator finger 39 imparts a rotative movement to the oscillating operator O and through the contact of the engaged stop 37 with the adjacent actuator arm 29 bodily moves the actuator over its pivot 26 in the direction of the engaged stop 23 of the bridge nose 34 until the upper end of the bearing 30 engages the upper side of the pin 26, placing the detent spring 35 under greater tension than normal. As the button 4 continues downward, its movement is transmitted through the pivoted finger 39 to impart a rotative movement to the actuator about its upper bearing on the pivot 26 causing the detent nose 34 to travel over the upwardly inclined surface of the contact 15 towards its high point, as shown in Figure 3, holding the contact with the terminal 10 closed under a slightly increasing tension of the spring 35 as the nose approaches the high point of the contact. During this rotative movement the pivot pin 26 acts as the fulcrum of a bell crank lever with the power being applied upon one arm by the finger 39 at the point of contact P between the oscillating operator end 37, and the actuator arm 29. During this movement, the point of contact P moves in the direction of the angular surface of the contact so that as the line from point P to the engaging point of the nose 34 approaches a right angle to the angular portion of the contact 15, the friction of the nose thereagainst is minimized. The movement of the nose 34 toward the high point of the contact increases the tension of the spring 35 so that just before the nose reaches the high point, the spring 35 bodily moves the actuator away from the contact 15 to bring the lower end of its bearing 30 into engagement with the under side of the pin 26 with the nose 34 still held in contact with the strip 15, and during this movement causes the actuator to rotate about the point P as a pivot. In other words, during the application of power at P, the bell crank lever rotates about the pivot 26 as a fulcrum, but as the nose 34 approaches the high point of the contact 15, power is applied at the lower end of the other arm of the bell crank lever causing it to rotate about the point P as a fulcrum, the elongated bearing 38 allowing sliding movement of the actuator about the fixed pivot 26. The movement imparted to the actuator by the stored up power in the spring 35 causes the nose 34 to snap over the high point of the contact 15 and to quickly extend the nose 34 to engage the stop 16 on the other end of the insulation projection I and thereby quickly oscillate the nose 34 to break engagement with the contact of the terminal 10.

From the above, it is seen that as soon as the pivoted finger 39 has rotated the oscillating operator O sufficiently to shift the actuator A from its normal pivot 26 to its eccentric pivot P, the spring 35 automatically completes the oscillation to snap the nose 34 out of engagement with the contact strip 15 and thereby break the circuit from terminal 11 to terminal 10. Upon release of the button 4, the spring 47 returns the button to the normal extended position, and the pivoted finger 39 is returned with its lower end above the oscillating operator O in line with the axis of the casing I. The opposite sides of the oscillating operator O, oscillating actuator and angular surfaces of projection I being similar, upon the next depression of the button, the end of the pivoted finger 39 will engage the opposite side of the oscillating operator O to first depress and impart

rotative movement to the actuator A from its normal to its eccentric pivot and snap the bridge nose to close the circuit.

This invention also contemplates its application to a two circuit switch, as shown in Figure 3. In this form, the insulating projection I carrying the contact strip 15 from the terminal 10 is provided with a complementary oppositely disposed surface 13a upon which is mounted a contact strip 15a, mounted upon the disc 7 and connected to a third terminal (not shown) in the same manner as the strip 15. The additional terminal is mounted upon a diameter of the disc passing through the center of the contact 10 and at a similar distance from the center thereof with the riveted head of the said terminal lying under the adjacent end portion 19 of the base 17 of the metallic actuator carrying bracket. The inner side of that end portion 19 is spaced apart from the adjacent contact strip 15a and is provided with an upwardly extending stop 23a bent back at an angle similar to the corresponding stop 23.

In this form, when the current continuing nose 34 is oscillated to break the circuit to the terminal 10 just as soon as it is snapped over the flat insulating surface 14, it immediately engages the contact strip 15a to complete the circuit to the additional terminal and then slides over said contact strip until it engages the stop 23a upon the end portion 19 of the metallic bracket, whereby upon manual depression of the button 4 the respective circuits from the terminal 11 to the other terminals are each closed and opened alternatively.

As shown and described, the parts of this improved switching mechanism excepting the push button, operating finger and contact carrier are all adapted to be formed of metal stamping to be easily and quickly assembled. The operating parts are dependable and the spring 35 for imparting the snap movement is fully protected, and the other parts are so constructed that the switch may be operated thousands of times without any of the parts deteriorating or getting out of order.

What I claim is:

1. An electric switch including, a casing, a contact carrier mounted therein, switching mechanism mounted on the carrier within the casing including a plurality of spaced apart contacts, a current continuing bridge mounted for oscillation and adapted alternately to make and break a circuit from one contact to another, an actuator mounted for oscillation about a pivot, an oscillating operator mounted on the actuator pivot having means to engage and oscillate the actuator, said actuator having a sliding engagement with its pivot and sliding engagement with the bridge, means maintaining the actuator in engagement with its pivot and with said bridge, means guided by the actuator pivot extending through the casing for manual reciprocation to oscillate the operator to engage and bodily move the actuator over its pivot and then rotate the actuator to travel in sliding engagement with the bridge, and means to shift the axis of rotation of the actuator from its normal pivot to a pivotal point eccentric thereto and thereafter snap the bridge to make or break the circuit therethrough.

2. An electric switch including, a cup-shaped casing, a contact carrier mounted upon the open end thereof, a switching mechanism mounted on the contact carrier including a plurality of spaced apart contacts, a metallic bracket electrically connected to one of said contacts, a current continuing bridge mounted for back and forth movement to

- make and break a circuit through the bracket from one contact to another alternately, an actuator mounted for oscillation about a pivot upon the bracket above the bridge, an oscillating operator mounted upon the actuator pivot having means to engage and oscillate the actuator, said actuator having a sliding engagement with its pivot and sliding engagement with the bridge, means maintaining the actuator in engagement with its pivot and with said bridge, means mounted upon the bracket extending through the casing for manual reciprocation to oscillate the operator to engage and bodily move the actuator over its pivot and then rotate the actuator to travel in sliding engagement with the bridge, and means to shift the axis of rotation of the actuator from its normal pivot to a pivotal point eccentric thereto and thereafter snap the bridge to make or break the circuit.
5. The structure of claim 2 wherein the manually operable means includes a frame embracing said bracket and guided for reciprocation by the actuator pivot.
6. The structure of claim 2 wherein the manually operable means includes a frame embracing said bracket and guided for reciprocation by the actuator pivot and wherein a spring is interposed between the bracket and frame normally maintaining the frame in its extended position.
7. The structure of claim 2 wherein the manually operable means includes a frame embracing said bracket and guided for reciprocation by the actuator pivot and wherein the upper end of said frame mounts a shouldered push button of insulating material mounted for reciprocation in the casing.
8. The structure of claim 2 wherein the manually operable means includes a frame embracing said bracket and guided for reciprocation by the actuator pivot and wherein the upper end of said frame pivotally mounts an operating finger to engage and impart a rotative movement to the oscillating operator upon reciprocation.
9. The structure of claim 2 wherein the manually operable means includes a frame embracing said bracket and guided for reciprocation by the actuator pivot, wherein the upper end of the frame pivotally mounts an operating finger to engage and impart a rotative movement to the oscillating operator upon reciprocation, and wherein a push button mounted for reciprocation in the casing closure is provided upon its inner surface with a recess to receive and embrace the upper end of the frame to coact with the top of the frame to pivot the operating finger.
10. An electric switch including, a cup-shaped casing, a contact carrier mounted upon the open end thereof, a switching mechanism mounted on the contact carrier including a plurality of spaced apart contacts, a central projection of insulating material upon the carrier having spaced apart oppositely disposed angular surfaces, a contact strip connected to one of the contacts mounted on one of the angular surfaces, a metallic bracket surrounding the said projection electrically connected to one of said contacts, a current continuing bridge mounted for back and forth movement over said angular surfaces to make and break a circuit through the bracket from one contact to another alternately, an actuator mounted for oscillation about a pivot upon the bracket above the bridge, an oscillating operator mounted upon the actuator pivot having means to engage and oscillate the actuator, said actuator having a sliding engagement with its pivot and sliding engagement with the bridge, means maintaining the actuator in engagement with its pivot and said bridge in engagement with the said projection, means mounted upon the bracket extending through the casing for manual reciprocation to oscillate the operator to engage and bodily move the actuator over its pivot and then rotate the actuator to travel in sliding engagement with the bridge, and means to shift the axis of rotation of the actuator from its normal pivot to a pivotal point eccentric thereto and thereafter snap the bridge to make or break the circuit.
11. An electric switch including, a cup-shaped casing, a contact carrier mounted upon the open end thereof, a switching mechanism mounted on the contact carrier including a plurality of spaced apart contacts, a central projection of insulating material upon the carrier having spaced apart oppositely disposed angular surfaces, contact strips mounted on each of the angular surfaces, a metallic bracket surrounding the said projection electrically connected to one of said contacts, a current continuing bridge mounted for back and forth movement over said projection and contacts thereon to make and break a circuit through the bracket from one contact to another alternately, an actuator mounted for oscillation about a pivot upon the bracket above the bridge, an oscillating operator mounted upon the actuator pivot having means to engage and oscillate the actuator, said actuator having a sliding engagement with its pivot and sliding engagement with the bridge, means maintaining the actuator in engagement with its pivot and said bridge in engagement with the said projection or a contact thereon, means mounted upon the bracket extending through the casing for manual reciprocation to oscillate the operator to engage and bodily move the actuator over its pivot and then rotate the actuator to travel in sliding engagement with the bridge and means to shift the axis of rotation of the actuator from its normal pivot to a pivotal point eccentric thereto and thereafter snap the bridge to make or break the circuit.

circuit through one or the other angular contacts.

12. An electric switch, comprising: a base; a casing, secured to said base, and having an opening in one of its walls; contacts carried by said base; a pivot structure, carried by said base, providing a pivot, and also having receiving means; movable means, swingable about said pivot, and movable into and out of engagement with said contacts; a lever swingable about said pivot, said lever and said movable means being so constructed and arranged that predetermined movement of said lever effects movement of said movable means; a manually actuated operator, slidably extending through the opening in said casing and having an abutment engageable with the inner surface of the wall adjacent said opening, said operator having a slot directed towards the interior of said casing; a motion transmitting member, having a portion rockably received in said slot, and a portion adapted to engage said lever to effect movement of said lever when said operator is moved inwardly of said casing; and resilient means, having one end disposed in the receiving means of said pivot structure, and having its other end bearing against said rockably mounted portion of said motion transmitting member, said resilient means being so constructed and arranged to urge said operator abutment into engagement with the inner surface of the wall adjacent the opening in said casing, and also to urge said motion transmitting member to predetermined relation with respect to said operator.

13. An electric switch, comprising: a base; a casing, secured to said base, and having an opening in one of its walls; contacts carried by said base; a pivot structure, carried by said base, pro-

viding a pivot, and also having receiving means; movable means, swingable about said pivot, and movable into and out of engagement with said contacts; a lever swingable about said pivot, said lever and said movable means being so constructed and arranged that predetermined movement of said lever effects movement of said movable means; a manually actuated operator, slidably extending through the opening in said casing and having an abutment engageable with the inner surface of the wall adjacent said opening, said operator having a slot directed towards the interior of said casing; a bracket member, having a portion disposed in said operator slot, said portion comprising spaced apart surfaces, and said bracket member also having legs provided with elongated slots, the margins of which engage said pivot to guide movement of said bracket and said operator; a motion transmitting member, having a portion rockably received between the spaced apart surfaces of said bracket member and the adjacent part of the slot in said operator, and a portion adapted to engage said lever to effect movement of said lever when said operator is moved inwardly of said casing; and resilient means, having one end disposed in the receiving means of said pivot structure, and having its other end bearing against said rockably mounted portion of said motion transmitting member, said resilient means being so constructed and arranged to urge said operator abutment into engagement with the inner surface of the wall adjacent the opening in said casing, and also to urge said motion transmitting member to predetermined relation with respect to said operator.

HARRY A. DOUGLAS.
